VELOCIPED CONSTRUCTION

Giles E. Bullock, Rochester, N. Y.

Application June 16, 1937, Serial No. 148,525

3 Claims. (Cl. 280—270)

This invention relates to velocipede constructions and has for its principal object to provide for a velocipede a strong and durable frame construction of novel design at a minimum cost for the manufacture thereof.

Another object of this invention is to provide the velocipede construction with a novel form of hollow backbone having a combined battery holder and headlight support incorporated therein.

A further object of this invention is to provide a velocipede with a novel fork construction for the mounting of the front wheel thereof.

Another object of this invention is to provide a velocipede with a novel hub construction for the rear wheels thereof.

Another object of this invention is to provide a velocipede with a novel pedal construction.

Another object of this invention is to provide a velocipede with a novel form of saddle construction.

All these and other objects and attendant advantages of this invention will become more readily apparent from the detailed description thereof which follows, reference being had to the accompanying drawings in which—

Figure 1 is a side elevation of the velocipede embodying the novel construction forming the subject matter of my present invention.

30 Figure 2 is a top plan view of the velocipede.

Figure 2A is a sectional view of the platform section of the velocipede, the section being taken on the line 2A—2A of Figure 2.

35 Figure 3 is a detail sectional view of the front end of the backbone of the velocipede, the section being taken on the line 3x—3x of Figure 1.

Figure 4 is a front elevation of the front end of the backbone of the velocipede.

40 Figure 5 is a sectional view of the pedal bearing construction in the front wheel fork of the velocipede, the section being taken on the line 5x—5x of Figure 1.

Figure 6 is a sectional view of the hub of the front wheel, the section being taken on the line

45 6x—6x of Figure 5.

Figure 7 is an enlarged sectional view of the fork construction, its mounting and steering connection, the section being taken on the line 7x—7x of Figure 1.

50 Figure 8 is a side elevation of the parts illustrated in Figure 7.

Figure 9 is a horizontal sectional view taken on the line 9x—9x of Figure 8.

55 Figure 10 is a vertical sectional view of the connection between the steering bracket and the handle bar.

Figure 11 is a horizontal sectional view taken on the line 11x—11x of Figures 7 and 8.

60 Figure 12 is a vertical sectional view of the

steering bracket taken on the line 12x—12x of Figure 10.

Figure 13 is an enlarged detail side elevation of the bearing for one of the pedals of the velocipede.

Figure 14 is a sectional view thereof taken on the line 14x—14x of Figure 13.

Figure 15 is a cross section of the pedal bearing taken on the line 15x—15x of Figure 14.

Figure 16 is a sectional view of one of the 10 complete pedals, the section being taken on the line 16x—16x of Figure 18.

Figure 17 is a front elevation of one of the pedals and end of the crank on which it is mounted.

15

Figure 18 is a side elevation thereof.

Figure 19 is a detail side elevation of the saddle of the velocipede.

Figure 20 is a bottom plan view thereof.

Figure 21 shows the saddle post and its support 20 and connection with the springs of the saddle.

Figure 22 is a horizontal section of the saddle post and spring support provided thereon, the section being taken on the line 22x—22x of Figure 21.

25

In the several figures of the drawings like reference numerals indicate like parts.

The velocipede construction forming the subject matter of my present invention embodies improvements of the velocipede construction illustrated and described in my prior Patent No. 1,984,916, issued December 18, 1934, and, as illustrated in the various figures of the drawings,

comprises a frame made up of a single tubular backbone 1 which has its rear end supported by 30 the platform 2 and rear axle 3. The latter is welded to the platform and projects from the ends thereof to have the rear wheels 4, 4 mounted to rotate thereon. To lock the wheels to the axle the outer ends thereof are reduced and threaded 35 to provide the shoulders 5 thereon and have a fixed hub 6 screwed thereagainst to hold the rotating hub 7 of the rear wheel against endwise movement on the axle.

The hubs 6 are provided with a combined shield 40 and handle 8 which is preferably circular in shape and concaved so as to extend over the hub toward the spokes of the rear wheel which is held in place by the hub. The diameter of the hub shield is enlarged to have it nest into the palm

45 of the hand while the fingers extend over the perimeter to provide a strong grip and considerable leverage for the rotation thereof in threading the hub onto or off the axle. For this reason the hubs 6 may be tightened or loosened on the

50 axle without the aid of a wrench.

As illustrated in Figures 2 and 2A the platform 2 is struck up at the middle and the rear end of the backbone 1 passes thru this struck up portion so as to project from the bottom of the platform 55 60

and have the axle 3 pass therethru for its support thereon and anchorage thereto. In this way a groove 9 is formed around the struck up portion of the backbone on the under side of the platform to have the backbone welded to the platform in this groove. In addition to this the axle 3 is welded to the backbone as indicated at 10, 10 and to the ends of the platform at 10A, 10A so as to rigidly connect the backbone, axle and platform and have the platform form a truss to rigidly support the backbone on the axle.

The forward end of the backbone is supported by the fork 12, the construction of which is illustrated in detail in Figures 7, 8, 11 and 12. For the mounting of the fork the top and bottom of the backbone has openings surrounded by tubular hub-like formations 13 and 14 which are struck out from the inside of the backbone in line with each other. A reinforcing sleeve 15 is telescoped into these hub formations and the collars 16 and 17 are telescoped into the ends of the reinforcing sleeve so as to have their outflaring outer ends overlap the ends of the reinforcing sleeve and the hub formations. The outer edges of the outflaring flanges of the collars are welded to the hub formations 13 and 14 to fasten the collars to the backbone and hold the reinforcing sleeve 15 in place in the backbone. The collars 16 and 17 provide spaced bearings on the inside of the hub formations at the top and bottom of the reinforcing sleeve in the backbone.

The fork is made up of sheet metal and comprises the head 18 which is upset in the middle to provide a socket 19 thereon. The fork shaped ends of the head are triangularly shaped and are lengthened by the arms 20 and 21 which, for this purpose, are provided at the upper ends with triangular recesses 22 to have the triangular ends of the head nest and interlock therewith and have their outer surfaces flush with the outside of the arms after the arms are welded to the triangular ends of the head in the assembly of the fork. The steering post 23 is welded into the socket 19 to form an integral part of the fork which projects thru the bearing collars 16 and 17 for rotation in the backbone. The shoulder of the fork, provided by the socket 19, engages the outflaring flange of the collar 17 and supports the backbone on the fork.

The steering post 23 projects from the bearing collar 16 on top of the backbone member for the attachment of the bracket 24 thereto. This bracket connects the steering post 23 with the handle bar 25. The bracket 24 is formed up of sheet metal with a split socket 26 at the lower end thereof and a clamp 27 at the upper end thereof. On each side of the split in the socket 26 is formed a lug 28 and a clamping bolt 29 passes thru these lugs to draw them and the wall of the socket together and firmly clamp the socket to the portion of the steering post over which the socket is telescoped.

The bracket is flattened toward the top and its outer end is bent back on itself and formed to provide a substantially cylindrical clamp 27 thereon. A clamping bolt 30 holds the free end of the clamp against the under side of the bracket as illustrated in Figure 10 so that by tightening the bolt the clamp 27 is contracted and grips the handle bar 25 which passes thru the clamp. In this way the handle bar is adjustably held in place at the forward end of the bracket 24.

The handle bar 25 is made up of a folded seam 75 tubing and to reinforce this tubing in order to

keep it from collapsing at the point where it is gripped by the clamp 27, a plug 32 is inserted into the tubing to brace the wall of the tubing from within and keep it from collapsing when the clamp is drawn tightly around it in fastening the handle bar to the bracket. 5

In the lower ends of the arms 20 and 21 of the fork are provided the bearings for the front wheel 33. For this purpose each of the arms has formed therein near its end thereof a short horizontal socket 34 with an inflaring flange 35 formed on the outside of the arm. An "oilless" bearing ring 36 is placed into the socket against the flange 35 and is held in place therein by means of the bushing 37 which is telescoped into the socket against the bearing ring from the inside of the arm. Each of the arms of the fork is thus provided with a self lubricating bearing in which the limbs 38 and 39 of the cranks 40 and 41 respectively are journaled for rotation in the 20 end of the arms of the fork.

The cranks 40 and 41 and their limbs 38 and 39 are fastened together by the bolt 42 which is butt welded to the end of the solid limb 39 of the crank 41 and extends thru the hollow limb 38 and crank 40. A nut 43 is threaded to the outer end of the bolt to hold the cranks together and draw their limbs into the ends of the hollow hub 44 of the front wheel 33. The hollow hub 44 of the front wheel is substantially square in cross section and the free ends of the limbs 38 and 39 are correspondingly square shaped in cross section so as to telescope into the ends of the hub to key the cranks to the hub and provide a driving connection between the cranks 40 and 41 and the hub of the wheel 43. In this way the movement of the cranks rotate the front wheel for the propulsion of the vehicle. 30

For the movement of the cranks their outer ends are provided with the pedals 46. These 40 pedals are mounted to rotate on the outwardly projecting portions of the crank and comprise a suitable rubber body with a hole 41 therein to have the crank engage therewith. The bearing for the pedal, which enables it to freely rotate 45 on the crank, comprises a pair of "oilless" bearing rings 48 and 49 which are telescoped over the horizontal crank's end and are held spaced thereon by means of the retaining bushing 50. The latter comprises a cylindrical sheet metal 50 housing which is longitudinally divided into two equal sections 51 and 52. The housing is formed so that each section is provided with a pair of substantially semicircular channels 53 and 54 which are spaced so that the opposing semicircular channels of each section form continuations of each other and engage and hold one of the oilless bearing rings in place between them. The two bearing rings are thus suitably spaced and locked into the sheet metal housing. To 60 lock the sheet metal housing to the crank an annular groove 55 is formed intermediate the crank ends and the two sections making up the sheet metal housing are provided with correspondingly semicircular inwardly projecting complementary 65 ridges 56 and 57 which engage into the annular groove in the crank end and keep the housing with the bearing rings against endwise movement thereon. To hold the two sections of the sheet metal housing together and in place on 70 the crank end, the rubber pedal is telescoped over the metal housing provided by the sections to have the yielding wall thereof tightly embrace the housing and hold the sections thereof together substantially embedded therein. The

bushing with its self lubricating bearing rings thus provides the bearing for the rotation of the pedal on the crank and at the same time automatically locks the pedal in place on the crank. 5 The outer end of each of the sections of the bushing is rounded in order to extend over and substantially cover the end of the crank. 10 The combined headlight support and battery holder of the velocipede are provided by the forward end of the backbone which, for this purpose, is expanded in the middle to provide the outwardly curved longitudinally extending supporting grooves 58 and 59 within the backbone. These grooves are shaped and spaced to receive 15 the cylindrical wall of a dry cell 60 between them in order to hold this cell centrally of the backbone and in line therewith in the front end thereof. The cell is inserted so that its positive center terminal 61 makes electrical contact 20 with the sleeve 15.

The headlight comprises a casing 31 of substantially the same cross section as that of the end of the back bone except for an expanded flange 62 which surrounds the rear of the casing. 25 This flange is adapted to telescope over the front end of the backbone and is suitably locked thereto to hold the headlight in place thereon. The front of the headlight casing is depressed to provide a reflector 63 with an opening in the center thereof and a threaded sleeve 64 extending rearwardly of the opening to provide a socket for the incandescent light 65. The switch for the headlight comprises a cross member 66 made up of insulating material which is mounted to move 30 transversely of the casing at the rear of the incandescent light and has its ends projecting from the sides of the casing so that it can be pushed back and forth therein. The switch member carries a small electrical contact button 67 in 35 the form of a rivet head at the front thereof so that by moving the cross member, the contact button is moved into and out of electrical contact with the end of the electric incandescent light 65. The rear of the cross member carries the yielding contact finger 68 which is electrically connected with the contact button 67 and provides the electrical connection between the incandescent light and the base of the shell 40 of the dry cell. The frictional and yielding contact of the contact finger with the base of the dry cell serves to hold the switch member in position with the contact button either in contact or out of contact with the incandescent light. 45

The frame of the velocipede and the casing of the headlight provides the electric circuit which connects the positive center terminal of the dry cell with the socket in which the incandescent light is mounted so that by moving the contact button into and out of contact with the end of the incandescent light by means of the switch member 66 while the spring finger is in contact with the base of a dry cell, the headlight is turned on and off. The yielding spring finger 68, aside from acting as a connection between the incandescent light and the dry cell, also serves as means for holding the dry cell yieldingly in place in the backbone with the center terminal thereof in electrical contact with the sleeve 15 which surrounds the steering post in the backbone. 55

The saddle 70 of the velocipede is mounted on the saddle post 71 which is adjustably clamped in place in the socket 72 provided for this purpose in the backbone. The saddle is preferably formed up of sheet metal and its novel feature 60 resides in the mounting of it on the saddle post by means of the spring 73. This spring is formed in one piece and comprises two coils 74 and 75, the top of each of which is suitably fastened to the under side of the saddle as illustrated in Figures 19 and 20. The connecting wire between the bottom of these coils is formed into a spring arm by having the projecting ends of the coil springs bent angularly toward each other and then cross each other twice to form first a small substantially rectangular loop 76 and then a large elongated loop 77. Both loops are bent so as to extend upwardly from the base of the coils 74 and 75 in front thereof and provide for the attachment of the outer end of the spring arm formed by the loops to the under side of the saddle at the forward end of the under side of the saddle. 65

Crossing the spring wire to form the loop 76 stiffens the arm at its point of attachment to the saddle post. For the attachment a fixed supporting washer 78 is carried by the post 71 and is formed so as to provide an angular seat on one side thereof to receive the rectangularly looped portion of the extension from one coil of the spring and hold it in place around one side of the saddle post. A clamping washer 79, formed so as to engage and hold the rectangularly looped portion of the extension from the other coil around the opposite side of the saddle post, is placed on top of the wire arm and suitably fastened to the saddle post to clamp the crossed wire portions of the arm together and to the saddle post. This form of attachment keeps the saddle from rocking laterally on the saddle post in that it stiffens the spring arm so that it cannot twist longitudinally on the saddle post. 70

I claim:

1. A fork support for supporting the backbone of a velocipede comprising a bi-furcated sheet metal head having tapered ends, a pair of sheet metal arms, tapered recesses in the end of each of said arms for the engagement of the tapered ends of said sheet metal head into said recesses for lateral and edgewise support of said arms on the ends of said head, a socket centrally of said head and a steering post carried by said socket for pivotal engagement in said backbone. 75

2. A fork support for velocipedes comprising a tubular backbone member, a sleeve member drawn outwardly from the top and bottom of said backbone member integrally therefrom, a sleeve extending transversely thru the backbone member to reinforce and connect said sleeve members within said backbone member, a bearing collar in each end of said sleeve and an out-flaring flange on each of said bearing collars for engagement over the ends of said sleeve and sleeve members so as to locate each bearing collar in a predetermined position in the ends of said sleeve and locate said sleeve in a predetermined position in said sleeve members. 80

3. In combination with the support of the backbone member of a velocipede the combination of a steering post journaled in said backbone member, an extension bracket for said steering post made up of a tubular member and having a tubular socket at one end for engagement over said steering post, the remainder of said tubular member being flattened longitudinally to provide a thin double walled end at the opposite end of the tubular bracket, a transverse loop formed by said double walled end of the tubular member, a handle bar extending thru said loop and means for contracting said loop around said handle bar. 85
